ATTORNEY

UNITED STATES PATENT OFFICE.

IRWIN COHN, OF NEW YORK, N. Y., ASSIGNOR TO IRWIN & COMPANY, INC., OF NEW YORK, N. Y., A CORPORATION OF NEW YORK.

TOY RATTLE.

Application filed October 23, 1926. Serial No. 143,575.

The object of the present invention is to provide a rattle for use by small children and comprising a doll's head having a novel eye construction, whereby the eyes may be moved by tipping the head in different positions, the specific object of the invention being to provide an article of the said class which shall be inexpensive to manufacture and wherein the eye pupil may have an oscillating or rotary motion to the extent of 360°, and the arrangement as such enabling the use of thin celluloid sheets for the entire article with the exception of the eye pupil and its hanging member.

The invention will be understood by reference to the accompanying drawing, in which—

Figure 1 is a plan view of a toy rattle constructed in accordance with the invention;

Figure 2 is a side elevation of the same partly in section (on the line 2—2, Figure 1), the handle being broken away;

Figure 3 is a plan view of the eye section of the rattle illustrating in dotted lines the movement of the eye pupil, and

Figure 4 is a detail view of the eye pupil and its hanging member.

With reference to the figures, it will be seen that the device comprises a head portion which may be made of two celluloid plates or sheets 1, 2, sheet 1 being formed into a face section and sheet 2 into the rear head sections, the two sheets being joined at 3. At 4 the head portion is secured to a handle 5 which may be of any suitable construction.

The head portion is formed of two spaced hemi-spherical depressions 6 serving as eye sockets, and covering each eye socket is a transparent disk 7 through which may be seen the eye pupil 8.

Each eye pupil 8 may consist of a bead or ball carrying a wire 9 which is projected through an opening 10 formed in the socket 6 and then is bent so as generally to conform to the curve of the socket. Thus the ball may have a rotary motion within the socket when the toy is tipped and may as-

sume various positions as shown by dotted lines a, Figure 3.

I am aware that attempts have heretofore been made to provide forwardly projecting globular transparent eye coverings, forming pockets for eye pupils. The present arrangement is an improvement on such devices in that the transparent covering 7 is united to the plate 1 at its marginal area and not at its edges as in such prior constructions, and the formation of socket 6 enables wire 9 to be sharply bent so as to hold the pupil 8 in position and yet freely permit the same to be moved in an arcuate path.

Having described my invention what I claim and desire to secure by Letters Patent is as follows:—

1. A toy rattle comprising a plurality of sheets of celluloid shaped and connected to form a head-like structure, spaced substantially spherical depressions formed in one of said sheets to provide eye sockets, each depression having an annular marginal shoulder, a transparent disk secured to said shoulder and covering the depression and a ball within the depression, the latter having a wire projecting through an opening in said depression, said wire being bent in such manner as to permit a bodily movement of the ball whilst holding it within its predetermined range of movement.

2. In toy rattles, a face portion of celluloid or the like and having spaced spherical depressions to form eye sockets, an annular shoulder at the margin of each socket, a substantially flat disk secured to said margin, the disk being transparent, and a ball in each socket, the ball carrying a wire projected through an opening in the socket and the wire being bent in substantially the curvature of the socket so as to permit bodily movement of the ball within the socket, whilst restraining it against movement outside of a predetermined range.

In testimony whereof I have signed my name to this specification.

IRWIN COHN.
